FIG. 2 is a view of a front side of the absorbent article substrate with a pattern of FIG. 1;

FIG. 3 is a view of the right side of the absorbent article substrate with a pattern of FIG. 1;

FIG. 4 is a view of the back side of the absorbent article substrate with a pattern of FIG. 1;

FIG. 5 is a view of the left side of the absorbent article substrate with a pattern of FIG. 1;

FIG. 6 is a view of the top side of the absorbent article substrate with a pattern of FIG. 1;

FIG. 7 is a view of the bottom side of the absorbent article substrate with a pattern of FIG. 1;

FIG. 8 is a perspective view of a second embodiment of an absorbent article substrate with a pattern;

FIG. 9 is a view of the front side of the absorbent article substrate with a pattern of FIG. 8;

FIG. 10 is a view of the right side of the absorbent article substrate with a pattern of FIG. 8;

FIG. 11 is a view of the back side of the absorbent article substrate with a pattern of FIG. 8;

FIG. 12 is a view of the left side of the absorbent article substrate with a pattern of FIG. 8;

FIG. 13 is a view of the top side of the absorbent article substrate with a pattern of FIG. 8;

FIG. 14 is a view of the bottom side of the absorbent article substrate with a pattern of FIG. 8;

FIG. 15 is a perspective view of a third embodiment of an absorbent article substrate with a pattern;

FIG. 16 is a view of the front side of the absorbent article substrate with a pattern of FIG. 15;

FIG. 17 is a view of the right side of the absorbent article substrate with a pattern of FIG. 15;

(Continued)

FIG. 18 is a view of the back side of the absorbent article substrate with a pattern of FIG. 15;
 FIG. 19 is a view of the left side of the absorbent article substrate with a pattern of FIG. 15;
 FIG. 20 is a view of the top side of the absorbent article substrate with a pattern of FIG. 15; and,
